Primary Examiner — Kendra Leslie Hamilton*Assistant Examiner* — Elizabeth S Struble(74) *Attorney, Agent, or Firm* — Goldstein Law Offices, P.C.(57) **CLAIM**

The ornamental design for a medical tape dispenser, as shown and described.

DESCRIPTION

FIG. 1 is a perspective view of a medical tape dispenser.

FIG. 2 is a top plan view of the medical tape dispenser.

FIG. 3 is a bottom plan view thereof.

FIG. 4 is a front elevational view thereof.

FIG. 5 is a rear elevational view thereof.

FIG. 6 is a right side elevational view thereof; and,

FIG. 7 is a left side elevational view thereof.

In the drawings, the equal-length broken lines depict portions of the medical tape dispenser that form no part of the claimed design.

1 Claim, 5 Drawing Sheets(56)
